ELECTRICAL SIGNALING ARRANGEMENT

Reginald Taylor and George Thomas Baker, Liverpool, England, assignors, by mesne assignments, to Automatic Electric Laboratories, Inc., Chicago, Ill., a corporation of Delaware

Application March 14, 1942, Serial No. 434,762
In Great Britain April 28, 1941

27 Claims. (Cl. 179—18)

The present invention relates to electrical signaling systems such as automatic telephone systems in which trains of impulses are utilised to effect the positioning of selective apparatus, and it is more particularly concerned with improved arrangements for responding to control impulses whereby greater reliability may be obtained when signaling over lines the characteristics of which cover a wide range.

The arrangement at present in general use for responding to trains of impulses comprises an impulse responding relay, usually designated "A," together with two slow-to-release relays "B" and "C." These latter relays are arranged to be dependent on the "break" and "make" periods respectively of relay A in that relay B operates as soon as relay A operates and then subsequently remains held due to its slug during the break pulses of each impulse train, while relay C operates on the first release of relay A via operated contacts of relay B and then remains held due to its slug during the make pulses of each impulse train. These relays will therefore fall away if the period during which they receive no current is greater than the release time determined by the slug.

In automatic telephone systems, in which the arrangements according to the invention have their widest field of use, trains of impulses are in the majority of cases generated by subscribers' dial impulse senders. These impulse trains may be transmitted over lines of varying length and characteristics to selecting switches at an exchange, and the A, B and C relay combination of each selecting switch must be able to respond satisfactorily to any combination of operating conditions within pre-arranged limits. Each of the slow relays B and C is dependent both on the rate or speed of the received trains of impulses which is determined by the adjustment of the subscribers' impulse senders and also on the pulse ratio of the received impulses which is governed chiefly by the line conditions which exercise a distorting effect on the ratio of the impulses transmitted thereover.

The operating range of the present B and C relay arrangement can be extended by making the release lag of the relays long enough to cover the variations in received impulse speed and ratio, but this solution to the problem will result in the case of the B relay in the undue delaying of the release of the selecting switch after the calling subscriber has hung up and in the case of the C relay will unduly increase the inter-digital pause required. A compromise must be

therefore effected and the relays B and C are accordingly adjusted to have release times within certain minimum and maximum limits to enable them to fulfill the diverse functions required of them to the best advantage. The object of the present invention is to provide an impulse responding arrangement of improved capabilities in which moreover it is possible to dispense with the critically-adjusted slow relays hitherto employed.

According to one feature of the invention, in an electrical signaling arrangement employing one or more trains of impulses for control purposes, an impulse responsive device including a timing device is arranged so that when the timing device has determined that the sum of the periods of which an impulse is made up exceeds a predetermined time interval regardless of the ratio of the different periods a control switching operation is effected, such predetermined time interval exceeding an interval substantially equal to the length of a complete impulse at the slowest tolerable speed.

According to another feature of the invention in an electrical signaling arrangement having control operations performed in response to one or more trains of impulses which consist of either interruptions of a closed circuit or closures of an open circuit, the sustained opening or closing 15 of said circuit effecting a further control operation, due to the interval from a given point in one impulse to substantially the same point in the next exceeding a predetermined value regardless of the ratio of the open and closed periods, a circuit change is effected at the receiving end the nature of which depends upon whether the control circuit is then open or closed.

A further feature of the invention is that in an electrical signaling arrangement having control operations performed in response to one or more trains of interruptions in a closed circuit the sustained opening or closing of which effects a further control operation, the timing operation which serves to initiate the further control operation is effected by a timing device whose operation is detectable independent of any moving part.

According to still another feature of the invention in an electrical signaling arrangement employing one or more trains of impulses for control purposes, a timing device is set in action on the satisfactory operation of the equipment which responds to individual impulses, is restored to normal at the commencement of each impulse and serves to effect a switching operation after

it has continued in action uninterruptedly for a predetermined time so as to indicate the end of a train of impulses.

The invention will be better understood from the following description of one method of carrying it into effect, reference being had to the accompanying drawings comprising Figs. 1-5. The invention is there shown applied to impulse response problems in automatic telephone systems in which circumstances it offers special advantages. Fig. 1 shows diagrammatically the connection between a subscriber's automatic telephone instrument or other form of impulse sender and a selector switch over a transmission line which may include impulse repeating arrangements; Fig. 2 is a form of the well-known graphical target diagram by means of which the performance of impulse responding arrangements both of the present and proposed type may be compared and analysed; Fig. 3 shows graphically an impulse train of two impulses; Fig. 4 shows a circuit diagram of a 100-outlet group selector switch of the vertical and rotary type arranged to have so-called rectangular motion, for instance of the mechanical construction disclosed in United States Patent No. 2,028,689, granted January 21, 1936, to R. N. Saxby, and Fig. 5 shows a circuit diagram of a 100-outlet final selector switch of the vertical and rotary type with a separate release magnet so that the wipers restore to normal by retracing the path over which they have been set.

Referring now to Fig. 1, the impulse sending device shown on the left is assumed to be arranged to deliver impulse trains of simple breaks and makes at a nominal rate of ten impulses per second, each impulse having a break-to-make ratio of 2:1, so that the break period is therefore 66.6% of the whole impulse, and the actual duration is 66.6 milli-seconds. Tolerance limits of 63% to 70% are assumed to be allowed for the break ratio, while the limits of impulse speed are from 9-11 impulses per second.

Referring now to Fig. 2, the various possible break periods in milli-seconds are plotted vertically against make periods horizontally, linear scales being adopted instead of the more usual logarithmic scales for the purpose of simplicity. Eight diagonal lines representative of various dial speeds from 7 to 16 impulses per second have been drawn, and their derivation will be appreciated from reference to the 10 impulses per second line. Here it will be seen that for all points thereon the sum of the break and make periods is 100 milli-seconds, the nominal dial speed of 10 impulses per second with a break-to-make ratio of 2:1 being represented on the diagram by the point X. The little quadrilateral in the centre of the diagram illustrates the previously mentioned impulse sender limits of 9-11 impulses per second and 63-70% break ratio.

Although the range of impulse sender speeds is limited to 9-11 impulses per second, the exchange selecting switches are designed to work between limits of from 7-14 impulses per second so as to give a further margin of tolerance on the adjustment of these pieces of mechanism and these minimum and maximum limits are indicated by making the 7 and 14 impulses per second lines dotted.

The transmission line between the impulse sending device and the selecting switch provides the main impulse distorting element, and although it has no effect on impulse speed, it may

distort the impulse ratio to such an extent that the input to the selector may lie anywhere along the line representative of the impulse speed in question. Hence for the various impulse speeds 5 7-14 impulses per second, the input to the selector switch may be anywhere within the area bounded by these dotted lines, together with the break and make axis. If the selector switch is to 10 allow of the widest possible variations in transmission line limits within the impulse speed range, it should be responsive to as much of this area as possible.

The working area of typical selector switch having the present A, B and C impulse responsive relay combination is bounded on one hand by the 15 7 and 14 impulses per second lines and on the other hand by the curves marked B and C which are respectively characteristic of the limits for the selector B and C relays. In the region between the B curve and the break axis the make periods are insufficiently long to allow the B relay to hold during the impulse train, while in the region between the C curve and the make axis the pulses delivered to relay C during the break 20 periods are insufficiently long to allow this relay to hold during impulsion. In these two areas therefore, the selector switch fails to meet possible received pulses owing to failure of the B or C relay as the case may be, and the arrangement according to the invention enables some or all of both of these areas to be brought within the 25 range of operation of the selector.

For this purpose the individual functions of the B and C relays are combined into a single impulse speed measuring circuit adapted to measure the duration of each complete impulse of a train, the measurement period extending between a particular point in one impulse and the same point in the succeeding impulse. Direct 30 measurement is not employed, it being merely determined whether the actual length of each impulse is greater or less than a fixed predetermined measured period which is equal or approximately equal to the longest length of impulse which can be tolerated, namely, a 143 milli-second impulse which correspond to the minimum dial speed of seven impulses per second.

The timing period is preferably arranged to 35 run from the beginning of the break period of the first impulse of a train and if a succeeding break is not received within this period, it is an indication either that the impulse train has finished or that the subscriber has hung up prematurely 40 and the selector switch concerned may accordingly be released. As the impulse length is unaffected by variations in impulse ratio, the arrangement according to the invention is dependent only on variations in speed and since 45 impulse speed is unaffected by varying line conditions, an improvement in the operating range is to be expected.

The improved impulse responding arrangement according to the invention will be better appreciated from the following description of its 50 application to two different automatic switches of the type used in telephone systems where, for the purpose of speed timing, use is made of a dischargeable condenser/resistance timing circuit which after a predetermined charging period builds up a sufficient potential across the condenser to strike a neon tube connected in circuit therewith and energise a relay to perform the required controlling function.

Considering now the circuit operation of the

group selector shown in Fig. 4, when the switch is seized, the loop extended forward from the subscriber's telephone instrument over the incoming negative and positive leads operates relay A, whereupon relay B is operated via resistance YA. This relay on operating, at armature *b1* applies a guard earth to the incoming private lead P, at armature *b5* lights the supervisory lamp LP, at armature *b6* completes a local locking circuit for itself and at armature *b8* extends dial tone from common lead 10 to the calling party, the tone finding a balanced circuit to line by induction through the windings of relay A.

The subscriber now dials the first digit of the wanted number and relay A responds thereto. On the first release of this relay, a quick discharge circuit is completed for condenser QB via the vertical magnet interrupter contacts *vm*, resting armatures *hr6* and *a1* and operated armature *b6*, resistance YA to battery so that this condenser QB, which is used for the impulse speed timing purposes, will not have any initial charge when it subsequently commences the timing operation. Relay A also at armature *a2* completes an operating circuit for the vertical magnet VM via rotary off-normal springs NR2, armatures *a2*, *h1*, *b2* and *hr5*, and test link TL to earth over common lead 14 via delayed release alarm equipment. Magnet VM on energizing raises the switch shaft and wipers to level 1, whereupon the off-normal springs N are mechanically operated, and magnet VM also opens its interrupter contacts *vm* so as to open the discharge path for condenser QB. When the off-normal springs are operated, contacts N2 complete a charging circuit for condenser QB via armature *b7* and resistance YB to positive battery which is connected to common lead 15. The values of the condenser and resistance and the positive battery potential are such that if this charging circuit is maintained uninterruptedly for a period of the order of 120 milli-seconds, which added to the vertical magnet operating time of, say, 20 milli-seconds gives a total period representative of the longest complete impulse which can be tolerated, condenser QB will be charged to the striking voltage of the neon tube NT. At the end of the first break period, relay A re-operates and opens the energising circuit of the vertical magnet at armature *a2* and at armature *a1* prevents a discharge circuit being completed for condenser QB after the interrupter springs *vm* close. During the ensuing make period condenser QB continues to charge.

Assuming that the digit dialled is 2 or more, the second break period will commence before condenser QB has time to charge up to the striking voltage of neon tube NT. Hence when relay A releases on the second break, a rapid discharge circuit is completed for condenser QB so as to restore this condenser to normal, while the magnet VM is energised a second time. Condenser QB again commences to charge on the operation of the vertical magnet interrupter springs and the cycle of operations described is repeated until the last impulse of the train is received.

Approximately 140 milli-seconds after the commencement of the break period of the last impulse, the voltage across condenser QB rises to the flash point of neon tube NT, whereupon the tube strikes and brings up relay H. This relay on operating disconnects any further circuit for the vertical magnet at armature *h1* and at the same armature completes a temporary locking

circuit for its right-hand winding and also a self-interrupted driving circuit for the rotary magnet RM via its interrupter contacts *rm*. Magnet RM on energising causes the wipers to cut in on to the first contact of the selected level and also opens its interrupter contacts *rm*, while the rotary off-normal springs NR are mechanically operated.

If the first outlet on the level is busy, the test 10 wiper P will encounter earth or booster battery metering potential, and accordingly when the magnet interrupter contacts *rm* open at the conclusion of the magnet strike, relay H will remain held over its left-hand winding from the potential encountered by the test wiper, the initial 15 operating circuit for relay H having of course been opened at this time by the extinction of the neon tube NT. Relay H therefore remains operated when magnet RM releases and when contacts *rm* re-close, relay H is held once again over its right-hand winding and the magnet again 20 energises to move the wipers on to the second outlet. This cycle of operations continues until a free outlet is encountered or until the wipers 25 are driven to the eleventh position.

If the former operation occurs, test wiper P fails to pick up potential on the contact it then 30 engages and accordingly relay H releases quickly when the contacts *rm* open, thereupon opening the driving circuit for the magnet and extending earth forward from armatures *b3* and *h2* over the test wiper P to busy the outlet seized. Relay H on releasing also brings up relay HR over resting armature *h3*, rotary off-normal contacts NR1 and armature *b5* to earth, and this 35 relay locks over its armature *h1* and at its armatures *hr2*, *hr3* and *hr4* switches the negative, positive and private conductors through to the succeeding switch selected. Relay A now releases, 40 whereupon relay B is short-circuited by the earth over armatures *a1* and *hr6* and commences to release slowly. Relay H is also re-operated over its left-hand winding by the earth fed forward over armatures *b1* and *hr4* and then subsequently 45 remains held from the holding earth which is returned backwardly over the private lead from the succeeding switch. When relay B finally releases, relay HR remains held from relay H over armatures *h1* and *h3* to earth.

50 When the parties clear at the end of the ensuing conversation, earth is removed from the P conductor at the final selector switch of the train and relay H thereupon releases, thus permitting relay HR to fall away. A self-interrupted driving circuit for the rotary magnet RM is then completed from the earthed delayed alarm release lead 14, link TL, armatures *hr5* and *b2*, contacts N1 and *rm*, magnet RM to battery. Accordingly the wipers are rotated clear of the banks, after which they fall and then rotate back below the banks under spring tension to their normal position where the homing circuit is opened at the off-normal springs N1. Preferably the rotary magnet is mechanically prevented from opening its interrupter contacts during the vertical release movement so that there is no tendency for it to chatter.

Returning again to the hunting operation of 70 the switch, if all outlets in the selected level prove busy, the wipers are rotated to the 11th step, where the test wiper P fails to encounter any busying potential and relay H releases as for the free outlet condition. An earth is thereupon extended over armatures *b3* and *h2* to oper-

ate an overflow meter connected to the 11th contact over the lead 16 and relay HR is operated in usual manner. The 11th step negative and positive outlets are wired back into the A relay circuit so that with the operation of relay HR, relay A will remain held over the calling subscriber's loop and thus relays B, H and HR also remain operated. At the 11th step cam contacts S2 and S3, busy tone and busy flash battery are extended over common leads 11 and 12 respectively, and thence through the windings of relay A to the calling line so that a busy indication is given to the calling party. When he subsequently hangs up, relay A releases and brings down relay B after a slight interval. Relays H and HR then release in turn and the previously traced circuit for the rotary magnet is completed and the switch wipers are restored as before.

Assuming now that after taking the selector switch into use the calling subscriber hangs up before dialling, relay A in releasing will produce the same effect as the first break impulse of an impulse train and will energize the vertical magnet VM, while relay B will remain locked to battery via resistance YA. The vertical magnet on energising raises the wipers to the first level, opens its interrupter contacts *vm* and brings about the operation of the off-normal springs, so that a charging circuit is completed for condenser QB. After the 120 milli-second timing period has elapsed, the neon tube NT will flash and operate relay H, whereupon the vertical magnet circuit will be disconnected at armature *h1* and a self-interrupted driving circuit for the rotary magnet RM will be completed at the same armature. The wipers will therefore cut in on the first level and the magnet RM will operate in a self-interrupted circuit until either a free outlet is found or the 11th stop is reached. Relay H then releases, since no holding circuit is completed thereto from the test wiper over its left-hand winding and relay HR operates. Since relay A is de-energised, relay HR now completes a circuit at armature *hr6* for short-circuiting and releasing relay B and on the release of this relay relays H and HR release in turn since no holding earth is fed back from the succeeding switch. A self-interrupted driving circuit is then again completed for the rotary magnet RM and the switch rotates its wipers clear of the banks and restores them to the home positions as in the case just described of release on receipt of a busy signal.

Considering now the operation of the 100-outlet final selector switch shown in Fig. 5, in this circuit the arrangements are such that if relay A is de-energised when the speed timing device comes into operation at the end of a timing period, the switch is at once restored to its normal position. Further, since the switch is to respond to two digits, the speed timing device on coming into operation at the end of the first impulse train is arranged, with relay A operated, to change over the impulsing circuit from the vertical to the rotary magnet in readiness for the second impulse train and is arranged at the end of the second train, with relay A operated, to initiate testing of the selected outlet.

Referring now to the circuit drawing, when the switch is seized, relay A operates and brings up relay B which locks over its armature *b1* and at armature *b3* applies guarding and holding earth to the incoming P lead.

On the reception of the first train of impulses, relay A responds and on the first release a dis-

charge circuit is completed for condenser QA via vertical and rotary magnet interrupter contacts *vm* and *rm*, resting armature *a1* and resistance YB, so that this condenser, which is used for the impulse speed timing circuits will not subsequently commence timing with any residual charge thereon. At the same time at armature *a2* an operating circuit is completed for the vertical magnet VM and this on energising raises the switch shaft and wipers to level 1 whereupon the off-normal springs N are operated and the interrupter contacts *vm* are opened to disconnect the discharge path for condenser QA. Off-normal contacts *N1* thereupon complete a charging circuit for condenser QA from positive battery over common lead 12, variable resistance YA, contacts NR2, resting armature *e2* and contacts *N1*, resistance YA being set to give a timing period of the order of 120 milli-seconds which added to the vertical magnet operating time of, say 20 milli-seconds, gives a total period representative of the longest complete impulse which can be tolerated. At the end of the first break period, relay A re-operates and opens the energising circuit of the vertical magnet at armature *a2* and at armature *a1* prevents a discharge circuit being completed for condenser QA after the interrupter contacts *vm* close. During the ensuing make period condenser QA continues to charge.

If the impulse train comprises two or more impulses, the second break period will commence before condenser QA has time to charge up to the striking voltage of neon tube NT and hence when relay A releases on the second break, a rapid discharge circuit is completed for condenser QA so as to restore this condenser to normal, while the magnet VM is energised a second time. Again condenser QA commences to charge on the operation of the vertical magnet interrupter springs *vm* and the cycle of operations is repeated until the last impulse of the train is received.

Approximately 140 milli-seconds after the commencement of the break period of the last impulse, the voltage on condenser QA rises to the flash point of neon tube NT, whereupon the tube flashes and brings up relay C. This relay on operating disconnects any further circuit for magnet VM at armature *c1*, and also renders relay B dependent on relay A so that the switch will release in a manner later to be described if relay A is normal at this time. Relay C also at armature *c2* completes a temporary locking circuit for itself, and at armature *c3* completes an energising circuit for the slow-to-operate relay E. On the operation of relay E, the impulsing circuit is changed over from the vertical magnet VM to the rotary magnet RM at armature *e4*, while a local locking circuit independent of armature *c3* is completed for relay E at armature *e5*. The holding circuit for relay C is opened at the same armature and this relay now releases, since condenser QA will have completed its discharge through neon tube NT by this time, while at armature *e2* the charging circuit for condenser QA is opened. Relay C on releasing, at armature *c1* re-prepares the impulsing circuit and at armature *c3* maintains the locking circuit for relay E independently of contacts NR4.

The switch is now ready to receive the second train of impulses and when this arrives, relay A releases on the first break as before and thereupon energises the rotary magnet RM and completely discharges condenser QA. Magnet RM

on energising cuts the wipers in on to the first contacts of the selected level and opens its contacts *rm* to disconnect the discharge circuit for condenser QA. The rotary off-normal contacts NR are also mechanically operated and at contacts NR2 complete a new charging circuit for condenser QA over the operated armature *e2* and contacts N1. Relay A re-operates at the end of the first break period and opens the energising circuit of the rotary magnet and also prevents a discharge circuit being completed for condenser QA after the interrupter contacts *rm* close. During the ensuing make period condenser QA continues to charge.

The circuit functions in the manner previously described if the second impulse train comprises two or more impulses and approximately 140 milli-seconds after the commencement of the break period of the last impulse of the train, the voltage on condenser QA rises to the flashing point of neon tube NT, whereupon the tube strikes and brings up relay C. This relay in operating, at its armature *c1* disconnects the impulsive circuit and opens the locking circuit of relay B, at armature *c2* completes a locking circuit for itself via the rotary off-normal contacts NR3, and at armature *c3* opens the holding circuit for relay E which therefore commences to release. During the release time of relay E, earth is extended over armatures *b1*, *c1* and *c3* and the lower winding of the switching relay H to the P wiper and the subsequent operation depends on whether the selected line is free or engaged.

If the selected line is free, wiper P will encounter battery and relay H therefore operates and at armature *h6* completes a locking circuit for itself, and at armature *h1* applies full earth to the P wiper to operate the called subscriber's cut-off relay in known manner. When relay E releases after its slow release period, a circuit for ringing the selected party's bell is completed as follows: earthed ringing current generator GNR, common lead 13, upper winding of the ring trip relay F, armatures *e1*, *f2* and *h2* to the negative line, the selected party's bell and condenser, the positive line and armatures *h3* and *h3* to battery via the ringing return resistance YC. During this time ringing tone is returned in a balanced circuit to the calling party by the connection of a ringing tone source over common lead 11 and armatures *h1* and *f4* to the middle winding of relay A. When the wanted party answers, relay F operates and thereupon at armature *f1* locks over its lower winding in series with the upper winding of relay H, at armatures *f2* and *f3* trips the ringing and completes the speaking circuit, and at armature *f4* opens the ringing tone circuit. Battery feed is supplied to the calling subscriber via the windings of relay A and to the called subscriber via the windings of relay D which is connected across the outgoing speaking leads by way of armatures *h4* and *h5*. Relay D operates over the called subscriber's loop and at its armatures *d1* and *d2* reverses the battery connections to give supervision to the calling side of the connection.

At the end of the conversation when the calling party hangs up, relay A releases and in turn releases relay B which thereupon brings about the release of relays C, F, H and D. At armature *b3* earth is removed from the incoming P conductor to bring about the release of the preceding switches. At armature *b4* earth is extended over the operated off-normal contacts N2

to energise the release magnet ZM which is connected to battery via suitable delayed alarm equipment connected to common lead 14; the wipers are thereupon restored to normal back-wardly over the path along which they have been set and the switch is completely released.

If the called party is busy when his line is seized, wiper P will encounter earth and relay H will fail to operate. Hence on the release of relay E, a circuit will be completed for relay G from earth over armatures *b1*, *c1* and *c3*, contacts NR1 and armature *h8*. Relay G thereupon at armature *g1* extends busy tone from common lead 10 to the middle winding of relay A from which it is returned to the calling party. When the calling subscriber hangs up, relays A, B, C and G are released and the switch is restored to normal as before.

Assuming now that after taking the switch into use the calling subscriber hangs up before dialling, relay A in releasing will produce the same effect as the first break of an impulse train and will energise the vertical magnet VM, while relay B will remain locked to earth over armatures *b1* and *c1*. The vertical magnet on energising raises the wipers to the first level, opens its interrupter contacts *vm* and brings about the operation of the off-normal springs, so that condenser QA, after being initially discharged on release of relay A, commences to charge on the operation of contacts *vm* and N1. After the predetermined timing period has elapsed, the neon tube NT flashes and operates relay C which locks to the earthed armature *b4* whereupon the circuit for both the vertical magnet and relay B is disconnected at armature *c1*. Relay B upon releasing, at its armature *b4* opens the holding circuit for relay C and at the same armature completes a circuit for the release magnet ZM so that the switch is restored to normal.

Similar remarks apply if the subscriber hangs up before dialling the final digit or during the dialling of the first or second digits received by the final selector in which case the speed timing arrangement, on coming into operation and operating relay C, finds relay A normal, whereupon relay B is immediately released to initiate the restoration of the switch wipers to normal. Normally, as has been described, the operation of relay C at the end of each timing period will, with relay A operated, initiate either the change-over from the vertical to rotary stepping or the testing of the called line according as to whether the first or second train of impulses received on the switch is concerned.

Reviewing the impulse speed timing arrangements, it will thus be seen that provided the impulses of a train follow one another at a spacing not exceeding the predetermined maximum value, that is to say, providing the dial speed is not less than seven impulses per second in the present instance, the speed timing device will be continuously reset by each succeeding impulse until the last impulse of the train has been received, after which the timing device comes into operation. In the case of a selector switch of the rectangular release type described, the selector is then caused to cut in in every case but subsequently in dependence on whether the calling subscriber has hung up or not, the switch is caused to remain connected through to a succeeding switch or to resume the rotary movement and carry the wipers clear of the banks, after which they restore to their normal position. In the case of a selector switch of the vertical and

rotary type with backward release, the operated or normal position of the A relay at the end of the time period will determine whether the switch will cut in or release. In the case of a final selector or other switch on which more than one digit is effective, at the end of the first impulse train the speed timing device on coming into operation prepares the switch in question for receiving the second digit.

It will have been noticed that in the arrangement described the speed timing measurements were taken from the beginning of each break impulse and this is preferred for the following reason. In case a selector switch is seized and the subscriber then hangs up his receiver without dialling, the only part of an impulse which is received is the break portion, and accordingly a release condition is treated as the first break impulse of an impulse train. If the predetermined time period elapses without a further pulse being received, this is evidence that either the simulated impulse or the impulse train proper has finished and the selector switch can then be caused to release or to proceed with the setting up of the connection in the manner already described.

The impulsive range of a mechanism utilising the arrangement according to the invention is that represented by the triangle in Fig. 2 which is bounded on its hypotenuse by the 7 impulses per second dotted line and on the other sides by the lines Mo and Mr which respectively indicate the limiting values of break and make period required to ensure satisfactory operation and release of the switch magnet. Two comparatively large areas have therefore been gained which were otherwise unobtainable with the A. B. C. relay triad arrangement previously employed. The only appreciable area not catered for by the scheme is that lying between the line Mo and the make axis and bounded by the dotted lines 7 and 14. In other words the scheme as already described is limited from further widening of its scope by the mechanical properties of the switch magnet which requires approximately 20 milli-seconds energisation time on each impulse to effect satisfactory response. Hence the impulse ratio cannot be allowed to vary to such an extent that the break periods to which the magnet responds are less than 20 milli-seconds duration. If desired however, this difficulty can be largely overcome by arranging that once the impulsive relay A releases in response to a break impulse, it cannot re-operate until the magnet has completed its operating stroke and has closed a pair of contacts. For this purpose the circuit of the A relay could include a make contact of relay A in parallel with vertical magnet make interrupter contacts and off-normal break contacts. With these arrangements when relay A has released in response to an impulse and opened its own contact it cannot re-operate until the vertical magnet interrupter contacts close. The off-normal break contacts are necessary to provide the initial circuit for relay A which would not otherwise be energised when the switch was taken into use.

Another advantage of the improved arrangement is that it can determine more quickly whether the end of an impulse train has arrived than has been possible hitherto, which provides a greater margin of safety for the interdigital pause period during which time a selector switch may have to perform a hunting operation for a free outlet to a subsequent switch. This feature

is particularly advantageous for use with digit-absorbing selectors of the rectangular release type dealt with in connection with Fig. 4 which have to restore to normal in a rectangular manner between two trains of impulses. The advantage gained over the previous triad arrangement can be illustrated by assuming that a selector receives standard impulses at the rate of ten per second with a break-to-make ratio of 2:1. In the existing arrangement the C relay which is operated in parallel or series with the magnet is timed to have a release lag of the order of 100-140 milli-seconds, and if this relay has the maximum release value of 140 milli-seconds, which value it will generally approach after a number of actual operations in practice, it cannot be decided that the impulse train has finished until 140 milli-seconds after the end of the last break impulse. Referring to Fig. 3, the last break impulse of a train of two impulses of the character described commences at point Y so that 140 plus 66.6 equals 206.6 milli-seconds will elapse from the beginning of the last impulse of the train before the decision can be made. In the method according to the invention, the speed timing commences at the point Y representing the beginning of the last break impulse, and assuming that the switch magnet has a maximum operate time of 20 milli-seconds, and that the condenser/neon tube timing circuit is set at a value of 120 milli-seconds, only a total of 140 milli-seconds from the beginning of the last break impulse need elapse before the switch can cut in and hunt or release. The new method thus in this instance gives a saving over 60 milli-seconds over the old, and though this saving increases with lower rates of dialling and decreases with faster rates of dialling, it is appreciable throughout the whole range of impulse speeds of from 7-14 impulses per second.

It is apparent that the improved arrangement is in no sense limited to the precise timing values described. The invention moreover is not limited to the exact electrical method of timing described as similar results could be obtained for instance by utilising a change of resistance due to a heating effect to alter the potential of the grid of a thermionic valve or alternatively a valve might be employed arranged so that it would emit electrons only after an interval sufficient to heat the cathode. Use could also be made of resettable electro-mechanical mechanisms for the same purpose. Furthermore the applications of the invention may include forms of selecting mechanism other than the direct step-by-step drive type, and in the case of application to switches of the common motor drive type, the use of electro-mechanical timing mechanisms operated from the same drive may prove the more desirable.

It will also be understood that though the arrangement described whereby the timing starts at the beginning of the break period generally offers certain advantages, the invention also covers timing from any given point in one impulse to the corresponding point in the succeeding impulse. This may be of more importance if the impulses are not simple makes and breaks but of a more complicated type, for instance reversals or composed of different frequencies of alternating current or combinations of direct and alternating current.

The invention accordingly provides an improved method of impulse response which operates on novel principles in that impulse ratio is

ignored and each impulse is dealt with as a whole. It will be appreciated that this method of attacking the problem differs fundamentally from impulse correction schemes which aim at re-adjusting the ratio of received impulses which have suffered distortion.

What we claim as new and desire to secure by Letters Patent is:

1. In a signaling system wherein different trains of impulses are transmitted over a signaling circuit at different times, wherein each of said trains comprises a variable number of spaced apart impulses, wherein all impulses in the same train are of a uniform duration and successive ones thereof are spaced apart by a uniform interval, and wherein the duration and spacing of impulses in the different trains are different, timing equipment, means for receiving said impulses and, responsive to the beginning of the first impulse of each train, causing said timing equipment to begin a timing operation, said means responsive to the beginning of each succeeding impulse of the train to cause said timing equipment to halt the timing operation previously started and to begin another timing operation, whereby the timing operation initiated by the beginning of each impulse except the last impulse in each train is halted responsive to the beginning of the next impulse in the same train, and means controlled by said timing equipment for halting the timing operation initiated by the last impulse in each train an arbitrary interval of time after the initiation of such impulse.

2. In a signaling system wherein different trains of impulses are transmitted over a signaling circuit at different times, wherein each of said trains comprises a variable number of spaced apart impulses, wherein all impulses in the same train are of a uniform duration and successive ones thereof are spaced apart by a uniform interval, and wherein the duration and spacing of impulses in the different trains are different, timing equipment, means for receiving said impulses and, responsive to the beginning of the first impulse of each train, causing said timing equipment to begin a timing operation, said means responsive to the beginning of each succeeding impulse of the train to cause said timing equipment to halt the timing operation previously started and to begin another timing operation, whereby the timing operation initiated by the beginning of each impulse continues until halted by the beginning of the next impulse, if one follows, regardless of the ratio of the duration of the impulse by which such timing operation was started to the interval between the ending of that impulse and the beginning of said next impulse, and means operated by said timing equipment if any timing operation is not halted within a predetermined interval of time after it is initiated.

3. In a signaling system wherein different trains of impulses are transmitted over a signaling circuit at different times, wherein each of said trains comprises a variable number of spaced apart impulses, wherein all impulses in the same train are of a uniform duration and successive ones thereof are spaced apart by a uniform interval, and wherein the duration and spacing of impulses in different trains are different, an impulse receiving device associated with said signaling circuit, said device operated in a certain way responsive to the beginning of each impulse and operated in a different way responsive to the end of each impulse, timing equip-

ment controlled by the operations of said first device in one of said ways but not in the other of said ways, said timing equipment effective, whenever one of said impulse trains is received,

5 to initiate a timing operation responsive to the first operation of said device in said one way, said timing equipment then effective responsive to each succeeding operation of said device in said one way to halt the timing operation which was initiated by the preceding operation of said device in said one way and to initiate another timing operation, and means operated by said timing equipment if any timing operation is not halted within a predetermined interval of time after it is initiated.

10 4. In a signaling system wherein a train of impulses is transmitted over a signaling circuit, wherein said train comprises a variable number of spaced apart impulses, and wherein all impulses in said train are of a uniform duration and successive ones thereof are spaced apart by a uniform interval, an impulse receiving device associated with said signaling circuit, said device operated in a certain way responsive to the beginning of each impulse and operated in a different way responsive to the end of each impulse, timing equipment controlled by said device to initiate a timing operation responsive to each operation of said device in one of said ways, said timing equipment also controlled by said device responsive to each succeeding operation of said device in said one way to halt the timing operation which was started responsive to the next preceding operation of said device in said one way.

15 5. In a signaling system, timing equipment, a circuit over which a variable number of spaced apart impulses are transmitted, said impulses all being of a uniform duration and successive ones of said impulses being spaced apart by a uniform

20 interval, an impulse receiving device associated with said circuit, said device operated a certain way responsive to the beginning of each impulse and operated a different way responsive to the end of each impulse, means controlled by each operation of said device in one of said ways to cause said timing equipment to start a timing operation, said means also controlled by each operation of said device in said one way to cause said timing equipment to halt any timing operation which may then be in progress as the result of a previous operation of said device in said one way, and another device operated by said timing equipment if any timing operation is not halted within a predetermined interval of time after it is initiated.

25 6. In combination, timing equipment, a device having a normal condition, means for operating said device a variable number of times in succession and for restoring said device to normal after each said operation, the successive ones of said operations occurring at regularly spaced intervals, means controlled by the first such operation of said device for causing said timing equipment to start a timing operation and controlled by each succeeding operation of said device, if any, for causing said equipment to stop the previous timing operation and start a new timing operation, and means operated by said timing equipment if any one of said timing operations is not stopped within a predetermined time after it is started.

30 7. A combination as claimed in claim 6, wherein said timing equipment is wholly static and performs said timing operation without any physical movement.

8. In a signaling system wherein a variable number of spaced apart impulses are transmitted over a signaling circuit, an impulse receiving device associated with said circuit, said device operated a certain way responsive to the beginning of each impulse and operated a different way responsive to the end of each impulse, a second device, means controlled by the operations of said first device in one of said ways but not in the other for operating said second device only when an operation of said first device in said one way is not followed by another operation thereof in said one way within a predetermined interval of time, and means under the joint control of said two devices operated differently depending upon the way in which said first device is operated at the time said second device operates.

9. In a signaling system wherein a variable number of spaced apart impulses are transmitted over a signaling circuit, an impulse receiving device associated with said circuit, said device operated a certain way responsive to the beginning of each impulse and operated a different way responsive to the end of each impulse, a second device, and means controlled by the operations of said first device in one of said ways but not in the other for operating said second device only when an operation of said first device in said one way is not followed by another operation thereof in said one way within a predetermined interval of time.

10. In a signaling system wherein a variable number of spaced apart impulses are transmitted over a signaling circuit, an impulse receiving device associated with said circuit, said device operated a certain way responsive to the beginning of each impulse and operated a different way responsive to the end of each impulse, a second device, time delay means conditioned by each operation of said first device in one of said ways to operate said second device after a predetermined interval of time, and means responsive only to another operation of said first device in said one way within said interval of time for preventing the operation of said second device by said time delay means.

11. A system as claimed in claim 10, wherein said time delay means includes a condenser, means for varying the charge on said condenser progressively, and means for determining when the charge on said condenser reaches a certain value.

12. In a signaling system wherein a variable number of spaced apart impulses are transmitted over a signaling circuit, an impulse receiving device associated with said circuit, said device operated a certain way responsive to the beginning of each impulse and operated a different way responsive to the end of each impulse, a condenser, a charging circuit and a discharging circuit for said condenser, and means controlled by each operation of said device in one of said ways for first rendering said discharging circuit effective to discharge said condenser and then, independently of the operation of said device in the other of said ways, substantially at once rendering said charging circuit effective to charge said condenser.

13. In a signaling system wherein a variable number of spaced apart impulses are transmitted over a signaling circuit, an impulse receiving device associated with said circuit, said device operated a certain way responsive to the beginning of each impulse and operated a different way

responsive to the end of each impulse, a condenser, means controlled by the operations of said device in one of said ways but not in the other, said means effective responsive to each 5 operation of said device in said one way first to bring said condenser to a predetermined state of charge and then to change its state of charge at a predetermined rate.

14. In a signaling system, a circuit over which 10 impulse trains are transmitted, a condenser, impulse receiving means effective in response to each impulse of a train first to bring said condenser to a predetermined state of charge and then to change its state of charge at a predetermined rate, whereby said condenser is not changed more than a certain amount from said predetermined state of charge so long as the successive ones of said impulses are received with certain frequency, and means operated under 20 control of said condenser whenever it is changed more than said certain amount from said predetermined state of charge.

15. In a signaling system, a circuit over which 25 impulse trains are transmitted, a condenser, receiving means effective in response to each impulse of a train first to discharge said condenser and then to charge said condenser at a predetermined rate throughout the balance of such impulse, whereby, so long as said impulses are 30 received with certain frequency, the charge on said condenser never reaches a predetermined value, and an electronic valve connected to said condenser and rendered operative responsive only to the charge thereon reaching said predetermined value.

16. In combination, a device, means for causing 35 said device alternately to assume two different conditions, a condenser, means operated whenever said device is changed from one of said 40 conditions to the other for first bringing said condenser to a predetermined state of charge and then changing its state of charge at a predetermined rate until said device again is 45 changed from said one condition to said other condition, whereby, so long as said device is changed from said one condition to said other condition with certain frequency, said condenser is not changed more than a certain amount from 50 said predetermined state of charge, and an electronic valve connected to said condenser and rendered operative responsive only to the charge thereon changing more than said certain amount from said predetermined state of charge.

17. In a signaling system wherein the flow of 55 current in a signaling circuit is transitorily interrupted at regular intervals for a certain number of times, a device, and means controlled by each 60 said interruption, but independently of the length of that interruption, for operating said device only when one of said interruptions is not followed by another within an arbitrarily fixed period which is slightly longer than said intervals.

18. In a signaling system, a device, a signaling 65 circuit over which trains of impulses are transmitted, each said impulse being divided into two complementary periods having a certain ratio to each other, and means controlled by the speed of successive impulses but independently of the ratio of the periods of any individual impulse to operate said device responsive only to the last impulse of a train.

19. In a signaling system, timing equipment, means for generating an electrical wave having a repetitive pattern, a device controlled by said 75 wave to operate in a particular way at the same

point in each repetition of said pattern, and means controlled by one operation of said device in said particular way to initiate the operation of said timing equipment and by a subsequent operation of said device in said particular way to halt the said previous operation of said timing equipment and initiate a fresh operation of said timing equipment.

20. In a signaling system, timing equipment, means for generating an electrical wave having a repetitive pattern, a device controlled by said wave to operate in a particular way at the same point in each repetition of said pattern, means controlled by one operation of said device in said particular way to initiate the operation of said timing equipment, said last means controlled by each subsequent operation of said device in said particular way to halt the operation of said timing equipment which was initiated by the immediately preceding operation of said device and to initiate a fresh operation of said timing equipment, and a second device controlled by said timing equipment to operate if any operation of said timing equipment is not halted within a predetermined time after it is initiated.

21. In a signaling system wherein a signal having a repetitive pattern is transmitted over a signaling circuit, a device, time delay means under the control of said signal and conditioned by the same point in each repetition of said signal pattern to operate said device after a predetermined interval of time, and means effective whenever said time delay means has been conditioned by an occurrence of said point in one repetition of said signal pattern for preventing said time delay means from operating said device only if the same point in the next repetition of said signal pattern occurs within said predetermined interval.

22. In a signaling system wherein a mechanism is moved step-by-step under control of an impulse train, means for receiving the impulses of said train and operating said mechanism one step for each received impulse, timing equipment controlled by said step-by-step mechanism to initiate a timing operation responsive to each step taken by said mechanism, and means operated by said timing equipment whenever said first means fails to receive a further impulse within a predetermined interval of time after the initiation of said timing operation.

23. In a signaling system wherein a mechanism is moved step-by-step under control of a train of spaced apart impulses, a device for receiving said impulses and causing said mechanism to step in accordance therewith, said device operated a certain way responsive to the beginning of each impulse and operated a different way responsive to the end of each impulse, a second device, time delay means conditioned by each operation of said first device in one of said ways to operate

said second device after a predetermined interval of time, and means responsive only to another operation of said first device in said one way within said interval of time for preventing the operation of said second device by said time delay means.

24. A system as claimed in claim 23, wherein said time delay means includes a condenser, means for varying the charge on said condenser progressively, and means for determining when the charge on said condenser reaches a certain value.

25. A system as claimed in claim 23, wherein said time delay means includes a condenser, means for varying the charge on said condenser progressively, and an electronic valve connected to said condenser and rendered operative responsive only to the charge on said condenser reaching a certain value.

26. In a signaling system wherein a mechanism is moved step-by-step under control of a train of spaced apart impulses, a device for receiving said impulses and causing said mechanism to step in accordance therewith, said device operated a certain way responsive to the beginning of each impulse and operated a different way responsive to the end of each impulse, a second device, means controlled by the operations of said first device in one of said ways but not in the other for operating said second device only when an operation of said first device in said one way is not followed by another operation thereof in said one way within a predetermined interval of time, certain equipment controlled by said second device upon operation if, at the time of such operation, said first device is operated in said certain way, and other equipment controlled by said second device upon operation if, at the time of such operation, said first device is operated in said different way.

27. In an automatic switch, a line over which spaced-apart impulses are received, a line relay associated with said line for responding to said impulses and operating said switch in accordance therewith, a condenser, means controlled by said relay and effective in response to the beginning of each impulse in a train first to discharge said condenser and then to charge said condenser at a predetermined rate until the beginning of the next impulse in said train, if one follows, whereby, so long as said impulses are received with certain frequency, the charge on said condenser never reaches a predetermined value, an electronic valve connected to said condenser and rendered operative responsive only to the charge thereon reaching said predetermined value, and a relay in the output of said valve controlled by the operation of said valve.
